CONVERTIBLE EARRING

John Chalikian, Herman Gold, and Abraham Gold, New York, N. Y.

Application December 17, 1951, Serial No. 262,053

2 Claims. (Cl. 63—14)

1

This invention relates to new and useful improvements in earrings.

More specifically, the present invention proposes the construction of an improved earring having a main body for extension along the front of the ear lobe and upon which a novel auxiliary ornamental member is pivotally mounted in a manner to have a position surrounding the main body or to have a position pended from the main body.

Another object of the present invention proposes the provision of a novel means for pivotally mounting the auxiliary ornamental member upon the main body so that the ornamental member can be easily pivoted between its two positions with relation to the main body.

Still further, the present invention proposes constructing the ornamental member so as to frictionally encircle the main body in a manner so that such frictional contact between the main body and the ornamental member will retain the ornamental member in its raised position engaged about the main body.

The present invention further proposes providing the main body on the side diametrically opposed to the side on which the ornamental member is pivoted to the main body with a stop member against which the ornamental member will engage when in the properly aligned position encircling the main body.

A further object of the present invention proposes the provision of a means for holding the ornamental member in a slight forwardly inclined position with relation to the main body in a manner to provide for a slightly different appearance of the earring.

As a further object, the present invention proposes forming the main body and the auxiliary ornamental member in several different shapes and with several different types of ornamentation so as to vary the appearance of the earrings embodying the basic principles of the present invention.

It is a further object of the present invention to construct earrings of the type described which are simple and durable and which can be manufactured and sold at reasonable cost.

For further comprehension of the invention, and of the objects and advantages thereof, reference will be had to the following description and accompanying drawing, and to the appended claims in which the various novel features of the invention are more particularly set forth.

On the accompanying drawing forming a material part of the present disclosure:

2

Fig. 1 is a front elevational view of the earring constructed in accordance with the present invention.

Fig. 2 is a view similar to Fig. 1, but with the auxiliary ornamental member shown in its lowered position.

Fig. 3 is an enlarged vertical sectional view taken on the line 3—3 of Fig. 1.

Fig. 4 is an enlarged vertical sectional view taken on the line 4—4 of Fig. 2.

Fig. 5 is an enlarged transverse sectional view taken on the line 5—5 of Fig. 2.

Fig. 6 is a view similar to Fig. 1 illustrating the earring constructed in accordance with a modification of the present invention and with dot and dash lines added to show the auxiliary ornamental member in its lowered position.

Fig. 7 is a vertical sectional view taken on the line 7—7 of Fig. 6.

Fig. 8 is an enlarged partial transverse sectional view taken on the line 8—8 of Fig. 6.

Fig. 9 is a view similar to Fig. 6, but illustrating the earring constructed in accordance with a further modification of the present invention.

Fig. 10 is a side elevational view of Fig. 9.

The earring, according to the first form of the present invention shown in Figs. 1 to 5, includes a main body 20 which is cast of precious, semi-precious or any other decorative metal. The main body 20 is illustrated as being dished in cross-section with its front face convexed and ornamented by a stone 21 set directly in the center thereof. The stone 21 in the illustrated form of the invention is a pearl which might be either real or imitation. At its bottom, the main body 20 is formed with a tubular member 22 for a purpose which will become clear as this specification proceeds.

The main body is to be positioned against the front of an ear lobe and extended rearward and upward from the tubular member 22; there is a stirrup 23. One end of the stirrup 23 is integrally formed with the tubular member 22 and has an internally threaded sleeve at its other end. A screw 25 is threaded through the sleeve 24 and is provided at its rear end with a knurled knob 26 by which a finger grip can be had on the screw for turning it in one direction or the other. At its front end, the screw 25 carries the usual pad member 27 for engaging the rear face of the ear lobe to clamp the earring in position thereon.

Engaged about the main body 20, there is an auxiliary ornamental member 28 which is preferably cast of the same material used for forming the main body. The auxiliary member 28 is substantially C-shaped in outline and is engaged

about the main body 20 with its ends defining its open side located at opposite ends of the tubular member 22. Those ends of the auxiliary member 28 are formed with inwardly directed end aligned trunnions 29 which are turnably fitted into the ends of the tubular member 22 for pivotally supporting the auxiliary member 28 upon the main body 20. The pivotal attachment of the auxiliary member 28 to the main body 20 permits the earring to be worn with the auxiliary member 28 in position encircling the main body 20, as shown in Figs. 1 and 3, or in a position depending from the main body 20, as shown in Figs. 2 and 4.

The auxiliary ornamental member 28 has an internal diameter of a size to fit frictionally about the main body 20 so that the frictional contact between adjacent surfaces of the main body 20 and the auxiliary member 28 in position engaged about the main body. For limiting pivoting of the auxiliary member 28 to a position in which it encircles the main body 20, the main body at the top thereof and diametrically opposite the tubular member 22 is formed with an upwardly projected stop member 30 against which the auxiliary member 28 engages, as best shown in Fig. 3.

The periphery of the auxiliary member 28 is ornamented by small stones 31 which are set into the periphery of the auxiliary member. It is preferred that those stones 31 be small pearls to complement the larger pearl used to ornament the main body 20.

From the foregoing description, it is apparent that the present invention proposes the construction of a novel earring which can be worn in either of two positions so as to create the appearance of two different earrings.

The modification of the invention shown in Figs. 6 to 8 is characterized by a main body 20^a encircled by and upon which an auxiliary ornamental member 28^a is pivotally mounted just as in the previous form of the invention. The auxiliary member 28^a is ornamented by being molded to have filigree or open work 31^a within the periphery thereof.

Furthermore, the modified form of the invention is characterized by the provision of a means for holding the auxiliary ornamental member 28^a in a forwardly and upwardly inclined position as shown by the full lines in Fig. 7. This is accomplished by providing the main body 20^a on opposite sides thereof with outwardly projected nipples 35, see particularly Fig. 8, arranged to be received within complementary recesses 36 in the auxiliary member 28^a when the auxiliary member is moved to the full line position shown in Fig. 7. The recesses 36 are formed in the inner periphery of auxiliary member 28^a at suitable locations to be engaged by the nipples 35.

The normal position of the auxiliary member 28^a in which it encircles the main body 20^a is illustrated by the dot and dash lines 28' in Fig. 7. The depended position of the auxiliary member 28^a with relation to the main body 20^a is illustrated by the dot and dash lines 28'' in Fig. 6.

In all other respects the form of the invention shown in Figs. 6 to 8 is similar to that described in connection with Figs. 1 to 5 and like reference numerals are used to identify like parts.

Referring now to the modification of the invention shown in Figs. 9 and 10, the earring is constructed to include a main body 20^b and an

auxiliary ornamental member 28^b which is pivotally supported on the main body. The main body 20^b and the auxiliary member 28^b differ from that illustrated in Figs. 1 to 5 only by the shapes thereof. The main body 20^b is of square outline and the auxiliary member 28^b is of rectangular outline to complement the shape of the main body. The depended position of the auxiliary member 28^b with relation to the main body 20^b is illustrated by the dot and dash lines 28''' in Fig. 9.

The form of the invention illustrated in Figs. 9 and 10 is in all other respects similar to that described in connection with Figs. 1 to 5 and like reference numerals identify like parts in all of the views.

It is to be understood that instead of the stirrup construction, any other known arrangement may be used for holding the earrings on a wearer's ears, such as clips, screw-ons for pierced ears, wire backs, non-pierced screws, etc. The shapes, ornamentation, material and the size of the earrings may also be changed as desired.

While we have illustrated and described the preferred embodiments of our invention, it is to be understood that we do not limit ourselves to the precise method herein disclosed and the right is reserved to all changes and modifications coming within the scope of the invention as defined in the appended claims.

Having thus described our invention, what we claim as new and desire to secure by United States Letters Patent is:

1. An earring, comprising a main ornamental body for extension along the front of an ear lobe, means for supporting said main body in position on said ear lobe, an auxiliary ornamental member engaged about said main body in the plane of the main body, means pivotally supporting said ornamental member in position on said main body to be pivoted between positions engaged about said main body or depended from said main body in prolongation thereof, and means for arresting pivoting of said auxiliary member in a position in which it will be inclined upward and forward from said main body, said means arresting pivoting comprising nipples projected from opposite sides of said main body, said auxiliary member having recesses located to be engaged by said nipples in the forwardly and upwardly inclined position of said auxiliary member.

2. The structure of claim 1 and including an upwardly projected stop member on said main ornamental body, said stop member being in the plane of the main body whereby the auxiliary member may be received within the main body against the stop member in the same plane thereof to effect the appearance of a unitary earring.
